OIL BURNER PUMPING UNIT

Laurence E. French, Sebastopol, Calif.

Application May 16, 1935, Serial No. 21,816

5 Claims. (Cl. 103—218)

The present invention relates to oil burners, and more particularly to burners of the oil-pressure atomizing type, commonly known as gun-type burners.

5 Oil burners of the above-described character usually comprise a rotary air fan or compressor, and also a fuel-oil pump mounted on the air-compressor housing, the fan and the pump being driven by a common electric motor. Oil pressure 10 is generated in the pump by means of gears which, because they operate at motor speed, communicate vibrations to the main frame of the machine and are communicated to the furnace. These vibrations and consequent noise are particularly objectionable in connection with oil-burner equipment used in domestic-home-heating apparatus, the requirements of which are quite exacting, because of the annoyance caused by the noise and the vibration to the occupants 15 of the house.

An object of the invention is to provide a new and improved oil burner of the above-described character, in which the said vibration and noise shall be greatly reduced. In the case of house-heating installations, the apparatus of the present invention is practically noiseless.

With these and other objects in view, as will appear from the following description, a feature of the invention resides in resiliently mounting, 25 as by means of a spring or rubber suspension, the motor shaft that carries the air fan, and also the motor shaft that carries the pump, thus providing for full-floating power.

The invention will now be described in connection with the accompanying drawing, in which Fig. 1 is an elevation of a preferred embodiment of the present invention, parts being broken away, and other parts being shown in dotted lines, the better to illustrate the invention; and Fig. 2 is a vertical section taken upon the line 2—2 of Fig. 1, looking in the direction of the arrows.

The fuel oil, entering through a central tube 2, is discharged into an air stream at the tip 45 of an oil-spray nozzle 4, mounted directly in an air housing 6. From the nozzle, the oil emerges into a fire box (not shown) in the form of a fine, combustible, atomized oil spray. A multiple-blade fan or air blower 12 draws air into a fan 50 or blower housing 8, through an opening 10, at low pressure, and discharges the air into the air housing 6. The air plays no function in atomizing the oil, but is supplied merely for the purpose of providing oxygen for combustion. The 55 blower 12 is mounted directly on the shaft 14

of an electric motor 16. The blower housing 8 and the air housing 6 are both attached to a framework 32 that is supported by pedestals 34 and 36. The oil is delivered to the central tube 2, at a pressure of about 100 pounds per square 5 inch, by an oil pump 18 that is mounted directly on another shaft 20 of the same electric motor 16. The shaft 20 is provided with a universal joint 21 in a housing 22, that is bolted to the oil pump 18 and to the electric-motor housing 10 24. The oil pump 18 is thus driven in perfect alignment with the fan shaft 14, so that the fan shaft 14 and the oil-pump shaft 20 operate, in effect, as a single shaft, having oppositely disposed parts 14 and 20. An ignition transformer 15 26 is carried below the motor-supporting frame or base plate 28 of the motor housing 24. The base plate 28 is secured, at one side, by bolts 30, to the framework 32 that carries the air housing 6 and the blower housing 8. The other side of 20 the base plate 28 is mounted upon a support 38 upon a third pedestal 40. The electric-motor housing 24 is thus supported by the base plate 28, the framework 32 and the support 38; and this motor housing 24 carries with it the blower 25 12 and the pump 18, through the medium of the shafts 14 and 20. The pump 18 may, however, be mounted firmly on the main frame of the burner, either on the blower side or on the motor side, or it may be bolted to the blower housing, 30 which produces the same vibration effect as when bolted to the main frame. Sometimes, the pump is driven through a flexible coupling, but the vibrations are not thereby prevented.

To reduce the noise and vibration produced 35 by the electric motor 16, the blower 12 and the oil pump 18, therefore, all that is necessary is to provide a floating, yielding or resilient suspension between the motor housing 24 and the base plate 28. In its preferred embodiment, this 40 resilient suspension comprises four bent, angle-shaped springs 42, one arm of each of which is fastened to the motor housing 24 by screws 44, and the other arm of each of which is secured by nuts 46 upon bolts 48, carried upon the base 45 plate 28, with rubber washers 50 interposed. The spring suspension may, however, take another form, and it may be constituted of other yielding, resilient connections, such as rubber. As the electric-motor housing 24, the motor 16 50 therein, the blower 12, the oil pump 18 and all the parts connected thereto, including the shafts 14 and 20, thus float, as a unit, upon the springs 42, the noise and vibration are substantially entirely eliminated. Among the parts so connected 55

to the oil pump 18 are a fuel-oil strainer 52 for filtering the oil before it reaches the pump, and a pressure-relief valve 19 for raising the oil to a desired, predetermined pressure, and maintaining this pressure constant, both integrally connected to the housing 22. It is necessary that the complete fuel-oil unit, including the oil strainer 52, the pressure-relief valve 19, and the oil pump disposed between them, be resiliently connected to float as a unit, as above described. If any one of these three elements 52, 19 and 18 of the fuel-oil unit thus directly connected to the motor 16 is brought into rigid contact with any portion of the blower case or the main frame of the burner, the vibrations from the oil pump 18 become transmitted through this rigid contact to the frame, and thence to the furnace, and from the furnace to the rooms above, causing an objectionable noise. When, on the other hand, the entire unit is supported on its resilient base, practically no sound is audible.

Washers like those indicated at 50 and other flexible couplings have been employed heretofore, but these are ineffectual to prevent vibration and noise because the vibrations are generated in the pump gears, and not in the motor coupling. For the same reasons, motors that are rubber or spring mounted are ineffective; they dampen the vibrations generated in the electric motor, but they have no effect on vibrations generated in the pump gears. According to the present invention, both the pump and the blower are directly mounted on the motor, on opposite sides thereof, so that the whole unit is completely resiliently mounted or floating by reason of the same resilient connections 42, 50 that resiliently separate the motor 16 from its base plate 28.

Modifications will occur to persons skilled in the art, and all such are considered to fall within the spirit and scope of the invention, as defined in the appended claims.

What is claimed is:

1. An oil burner pumping unit comprising a fuel-oil pump for supplying oil to a fire box, an air-blower fan for supplying air to the fire box to support combustion of the oil, a motor upon which the oil pump and the air-blower fan are solely-supported and connected so as to be driven thereby, means for supporting the motor together with the oil pump and the air-blower fan, and means providing a yielding connection between the motor and its said supporting means to reduce noise and vibration.

2. An oil-burner pumping unit comprising a supporting frame, a motor housing, means yieldingly connecting the motor housing to the supporting frame, an electric motor in the motor housing and provided with oppositely extending shafts, an air-blower fan mounted directly on one of the motor shafts, a rotary fuel-oil pump supported solely by the motor housing and having a shaft connected directly to the other motor shaft, a fuel-oil strainer and a pressure-relief valve rigidly connected with the pump, and a universal-joint connection between the pump shaft and the said other motor shaft.

3. An oil-burner pumping unit comprising a support, a motor housing, means yieldingly connecting the housing to the support, a motor in the housing having two oppositely disposed shafts, a rotary fuel-oil pump for supplying oil to a fire box and provided with a shaft, a fuel-oil strainer and a pressure relief valve rigidly

connected with the pump, means supporting the oil pump, the strainer and the valve as a unit solely from the housing, an air-blower fan for supplying air to the fire box to support combustion of the oil, means connecting the pump shaft to one of the motor shafts, and means connecting the air-blower fan to the other motor shaft, whereby the housing, the said unit, the motor and the air-blower fan are floatingly supported as a unit by the support through the yielding-connecting means to sound-insulate the moving parts of the motor, the pump and the air-blower fan from the support.

4. An oil-burner pumping unit comprising a support, a motor housing, means yieldingly connecting the housing to the support, a motor in the housing having two oppositely disposed shafts, a rotary fuel-oil pump for supplying oil to a fire box and provided with a shaft, a fuel-oil strainer and a pressure-relief valve rigidly connected with the pump, means supporting the oil pump, the strainer and the valve as a unit solely from the housing, an air-blower housing and an air tube mounted independently of the support for the motor, the air-blower housing having an opening through which one of the motor shafts freely extends, an air-blower fan in the air-blower housing for supplying air through the air tube to the fire box to support combustion of the oil, means connecting the air-blower fan to the said one motor shaft, and means connecting the pump shaft to the other motor shaft, whereby the motor housing, the said unit, the motor and the air-blower fan are floatingly supported by the support as a unit through the yielding-connecting means independently of the air-blower housing and the air tube to sound-insulate the moving parts of the motor, the pump and the air-blower fan from the support, the air-blower housing and the air tube.

5. An oil-burner pumping unit comprising a support, a motor housing having oppositely disposed openings, means yieldingly connecting the housing to the support, a motor in the housing having two oppositely disposed shafts extending freely through the respective openings in the housing, a pump housing connected to the motor housing so as to be supported solely thereby, the pump housing having an opening through which one of the shafts freely extends, an air-blower housing and an air tube mounted independently of the support for the motor, the air-blower housing having an opening through which the other shaft freely extends, a rotary fuel-oil pump in the pump housing for supplying oil to a fire box, the pump having a shaft connected to the said one motor shaft, a fuel-oil strainer and a pressure-relief valve rigidly connected with the pump, an air-blower fan in the air-blower housing for supplying air through the air tube to the fire box to support combustion of the oil, and means connecting the air-blower fan to the said other motor shaft, whereby the motor housing, the pump housing, the motor, the pump, the strainer, the valve, the air-blower fan and the shafts are floatingly supported by the support as a unit through the yielding-connecting means independently of the air-blower housing and the air tube to sound-insulate the moving parts of the motor, the pump and the air-blower fan from the support, the air-blower housing and the air tube.
